UNITED STATES PATENT OFFICE.

SIMON ROSS, OF CINCINNATI, OHIO.

SHOE-UPPER TURNING AND BEADING MACHINE.

SPECIFICATION forming part of Letters Patent No. 606,301, dated June 28, 1898.

Application filed June 1, 1897. Serial No. 638,999. (No model.)

To all whom it may concern:

Be it known that I, SIMON ROSS, residing at Cincinnati, in the county of Hamilton and State of Ohio, have invented certain new and 5 useful Improvements in Shoe-Upper Turning and Beading Machines, of which the following is a specification.

My invention relates to that class of shoe-upper turning and beading machines shown 10 in Letters Patent of the United States No. 432,902, granted July 22, 1890.

The object of the present invention is to simplify the driving apparatus and make the same more durable.

15 Another object of my invention is to provide means for controlling the movement of the turning-iron and to adjust the driving mechanism for the same to fixed positions or to control the same by treadle movement, 20 as desired.

The various features of my invention are more fully set forth in the description of the accompanying drawings, making a part of this specification, in which—

25 Figure 1 is a front elevation of my improvement. Fig. 2 is a longitudinal and vertical section of my improvement, showing the driving mechanism in elevation. Fig. 3 is a section on line $x-x$, Fig. 2. Fig. 4 is a section 30 on line $y-y$, Fig. 2.

A represents the base on which the shell-frame B rests. C represents the stationary jaw, and D the movable jaw, of the beader. E represents the hollow standard in which the 35 turning-iron reciprocates. F represents the main shaft, and G the sleeve in which the same journals. These parts are substantially the same as shown in my said former patent.

The driving mechanism of my improvement 40 is constructed as follows:

a represents a crank or wrist pin attached to shaft F.

d represents a connecting-rod journaled on crank-pin a and to the ear e of the yielding arm f , which is loosely hinged to the movable jaw D.

50 b represents an extension of the connecting-rod d , carrying a secondary wrist-pin c . In order to cushion the movement of said jaw D, which is oscillated on its pivot D' by connecting-rod d , I provide the following mech-

anism: h represents a coil-spring interposed between arm f and the outer end of the jaw D. i represents a rubber spring between the horizontal portion of jaw D and the tightening-bolt g' .

I represents simply a washer between the nut and cushion i . This cushions the downward movement of arm f and the outward movement of jaw D, while spring h cushions 60 the stroke of said jaw D against the material held between it and the stationary jaw C.

j represents a nut for regulating the tension of the coil-spring h . Thus I obtain a noiseless movement of jaw D and its driving mechanism, as well as cushioning its movement at each end of the stroke.

The turning-iron is driven in unison with the beading-jaw by the following mechanism: To the supplemental wrist-pin c is pivoted a 70 link k , the other end of which is pivoted to the rock-arm l , which oscillates on the center l' .

H represents the turning-iron, reciprocating vertically in guides of the standard E, the lower end of which is pivoted upon the center m of rock-arm l . In order to regulate the protuberance of the turning-iron H beyond the guides n , between which it reciprocates, I 75 pivot the rock-arm l in the following manner:

K represents an oscillating arm loosely 80 hinged at one end to the frame of the machine by the center-bolt o , which is connected to the head O by a pivot o' . The end of said arm is made convex and engages in a concave seat formed in the frame and acts as the center on which said arm K rocks, the pivot-bolt o serving to hold said arm firmly to its seat.

In order to take up lost motion and to prevent rattling and jar, I provide a spring-washer p , interposed between the set-nut q 90 and the frame. I thus secure a noiseless movement of said arm K. Rock-arm l is connected to this arm by means of a link r , pivoted thereto, as shown in Fig. 2. Arm K is provided with a shaft L, which projects outward through the segmental slot M in the side of the base-frame. This shaft journals in the sleeve P and in the hub P', formed integral with the arm K. R represents a set-nut 95 tapping on said shaft L. When said nut R is slackened, the shaft L is free to move up and down in the slot M. When moved down-

ward, it depresses the arm K and lowers the journal of the turning-iron H by lowering the center on which rock-arm l journals. The link r, turning on its center, accommodates itself to the new position. By means of the shaft L and set-nut R the position of arm K can be secured at any desired fixed point; but in case it is desired to have the movement of the turning-iron under the control of a treadle, so that the operator can cause the turning-iron to protrude more or less at will, the set-nut is slackened and the treadle S applied by connecting rod S' to the ear s of sleeve P.

15 By means of the combination of wrist-pin c with the crank-pin a the driving mechanism is simplified and operates the turning-iron and beader-jaws with much less number of parts and less friction and more positively than in the device of my said former patent. I am also enabled to control the stroke of the turning-iron either by fixed adjustment or by the treadle movement, as desired. This method of construction is much superior to 25 my said former invention in point of durability, which is the most important consideration in machines of this class on account of the high rate of speed at which they are driven.

Having described my invention, I claim—

30 1. In a shoe turning and beading machine, in combination with the oscillating beader-jaw, a plate loosely hinged to the arm thereof, driving mechanism, a rod connecting said plate with the driving mechanism, and springs 35 interposed between the working parts of said plate and jaw to cushion the movement of the latter, substantially as described.

2. In a shoe turning and beading machine, mechanism for reciprocating the turning-iron 40 comprising a vertically-adjustable movable

arm, a rock-arm centrally mounted thereon and having hinge connection with the turning-iron, driving mechanism, and crank-and-link mechanism connecting the rock-arm and driving mechanism, substantially as described. 45

3. In a shoe turning and beading machine the combination of the oscillating arm K pivoted at one end to the frame of the machine and the link r connected to the rocking driving-arm l to which the turning-iron is hinged, and means for locking said oscillating arm in various positions, substantially as specified. 50

4. In a shoe turning and beading machine the combination of a stationary and an oscillating beader-jaw, driving mechanism connected to the oscillating jaw, lever mechanism connecting said driving mechanism to the turning-iron, said lever mechanism being mounted upon a vertically-adjustable arm 60 whereby the stroke of the turning-iron is controlled, substantially as specified. 55

5. In a shoe turning and beading machine the combination with the main shaft, of a connecting-rod pivoted thereto, and to a 65 yielding arm for driving the oscillating beader-jaw, a rock-arm connected at one end by means of a link to the driving mechanism and at the other end to the turning-iron, said rock-arm being pivoted at a point between 70 its ends to a vertically-adjustable arm movably secured to the frame of the machine, substantially as specified.

In testimony whereof I have hereunto set my hand.

SIMON ROSS.
